UNITED STATES PATENT OFFICE

170,166

MAILBOX OR SIMILAR ARTICLE

Nathan W. Roop, Columbus, Ohio, assignor to Columbus Plastic Products, Inc., Columbus,
Ohio, a corporation of Ohio

Application September 22, 1952, Serial No. 21,540

Term of patent 14 years

(Cl. D74—9)

To all whom it may concern:

Be it known that I, Nathan W. Roop, a citizen of the United States, residing at Columbus, in the county of Franklin and State of Ohio, have invented a new, original, and ornamental Design for a Mailbox or Similar Article, of which the following is a specification, reference being had to the accompanying drawing, forming a part thereof.

Fig. 1 is a front perspective view of a mailbox or similar article showing my new design;

Fig. 2 is a top plan view thereof;

Fig. 3 is a rear perspective view of the mailbox; and

Fig. 4 is a side elevational view thereof.

I claim:

The ornamental design for a mailbox or similar article, substantially as shown.

NATHAN W. ROOP.
